UNITED STATES PATENT OFFICE.

JOHN R. TOWNSEND, OF SOUTH BEND, INDIANA, ASSIGNOR, BY MESNE ASSIGNMENTS,
TO WESTINGHOUSE ELECTRIC & MANUFACTURING COMPANY, OF EAST PITTS-
BURGH, PENNSYLVANIA, A CORPORATION OF PENNSYLVANIA.

MINE-LOCOMOTIVE HEADLIGHT.

Application filed October 2, 1922. Serial No. 591,795.

This invention relates to headlights, more particularly to a special form of headlight adapted for use on mine locomotives.

In locomotives, especially in mine locomotives, it is necessary that the headlight construction shall be such as to substantially prevent vibration therein, since vibration results in a flickering light which is confusing to the engineer, and the life of the lamp filament is greatly decreased by shocks and jars. It is, therefore, an object of this invention to provide a headlight mounting which shall absorb the ordinary shocks and jars incident to operation of the locomotive, to increase the efficiency of the headlight and to increase the life of the lamp filament.

It is a further object of my invention to provide a construction which shall prevent a continued swinging movement, in any direction, of the beam of light issuing from the lamp.

It is a still further object of my invention to provide a structure which shall be comparatively simple, inexpensive to manufacture and efficient in operation.

Hitherto, many attempts have been made to provide a headlight structure having the characteristics desirable for locomotive service. To accomplish this, it was proposed to suspend the lamp within the casing by means of radial springs attached thereto and holding the same in proper position. However, such construction did not accomplish the result, since it allowed movement of the lamp in other than radial directions. To remedy this, it was proposed to place a flat leaf spring behind the lamp structure which should tend to hold the same in the proper position. This also failed to accomplish the result, since the leaf spring merely tended to limit the swinging motion of the lamp and did not prevent it.

My invention is directed to a similar structure including a plurality of sets of springs which are so arranged as to exert a yielding supporting force upon the lamp and its mounting in all directions. Specifically, I provide a set of radial springs which converge diagonally toward a plane passing through the headlight structure perpendicularly to the line of motion of the locomotive. A second set of springs also converges to said plane but from the opposite side there-

of. By reason of such an arrangement of springs, the lamp and its mounting are 55 yieldingly held against movement in all directions, and the tension of said springs almost entirely prevents any swinging or "whipping" movement of the lamp.

In the accompanying drawing, constituting a part hereof and in which like reference characters designate like parts,

Fig. 1 is a front elevational view of my new headlight;

Fig. 2 is a cross-sectional view thereof 65 taken along the line II—II of Fig. 1, and

Fig. 3 is a cross-sectional view taken along the line III—III of Fig. 1.

The casing 1 of the headlight is provided with a base 2 providing means for securing the headlight to the locomotive. Within the casing is a spider consisting of cross pieces 3 and 4 secured together by a rivet 5. A ring is riveted to the free ends of members 3 and 4. The spider is secured to the casing 70 in any suitable manner, as by bolts 7 extending through the ring 6.

The lamp mounting or support 8 has a reflector 9 secured thereto by rivets. In the lower portion of said mounting is a lamp base 10 having a lamp socket 11 therein projecting through an opening in the reflector 9. A lamp 12 is mounted in said socket.

A set of tension springs 13, here shown as two in number, is secured to the rear of 85 the lamp support at 14 and to one of the cross pieces of the spider at 15, said springs 13 converging diagonally in a vertical plane to a plane coincident with the rear portion of the lamp support. Radial tension springs 16 90 are secured to the sides of the support 8 at points 17 and to the cross pieces of the spider at points 18, said radial springs also converging to the same plane, being diagonally arranged within the casing.

A lens 19 is secured within a holding ring 20 having radial arms 21 merging into a central ring 22, the entire structure being adapted to protect the lens 19 from injury. Interposed between the ring 20 and the lens 100 19 is a non-metallic washer 23, and a ring 24 on the opposite side of the lens holds the same in fixed relation to the ring 20 by means of screws 25 secured into the annular extension 26 of ring 20. The lens and its supporting structure are secured to the casing 105

by cooperating threaded portions 27 on the extension 26 of the ring and the front end of the casing 1.

It will be noted that my invention provides a headlight structure comprising a relatively small number of parts which may be readily assembled and as readily disassembled for purposes of inspection or repair. In order to take the entire structure apart, 10 it is merely necessary to unscrew ring 20 and then to remove screws 7.

A further advantage in this construction is the plurality of sets of springs secured to the cross pieces of the spider and converging 15 diagonally and secured to the support 8. The construction prevents any swinging movement of the lamp relative to the casing, at the same time allowing sufficient motion thereof to greatly decrease the danger of 20 breaking of the lamp filament during operation of the locomotive and to prevent flickering of the beam of light.

I claim as my invention:

1. A headlight structure comprising a 25 casing, a spider therein, a support within said spider and springs secured to the front

and rear portions of said spider and converging to points of attachment in said support lying in a plane intermediate said front and rear portions.

2. A headlight structure comprising a casing, a spider therein, a support within said spider, springs secured to the front and rear portions of said spider and converging to points of attachment in said support lying in a plane intermediate said front and rear portions, said plane being perpendicular to the axis of said casing and means for holding a lamp in said support.

3. A headlight structure comprising a casing, a spider therein, a support within said spider, springs secured to the front and rear portions of said spider and converging to points of attachment in said support lying in a plane intermediate said front and rear 45 portions, a reflector mounted on said support and means for holding a lamp in said support.

In testimony whereof, I have hereunto subscribed my name this 30th day of August, 50 1922.

JOHN R. TOWNSEND.
